Primary Examiner — Brett Miller(74) Attorney, Agent, or Firm — Porzio Bromberg & Newman P.C.(57) CLAIM

We claim, the ornamental design for a hotel room, as shown and described.

DESCRIPTION

FIG. 1 is a front view, showing our new design;
 FIG. 2 is a rear view thereof;
 FIG. 3 is a top view of FIG. 2; and,
 FIG. 4 is an end view thereof.
 The broken lines shown in the figures form no part of the claimed design.
